UNITED STATES PATENT OFFICE.

JOHN F. MALTHANER, OF ATLANTA, GEORGIA.

RECORDING-TELEPHONE.

1,290,621.

Specification of Letters Patent. Patented Jan. 7, 1919.

Application filed August 3, 1915. Serial No. 43,471.

To all whom it may concern:

Be it known that I, JOHN F. MALTHANER, a citizen of the United States, and resident of Atlanta, county of Dekalb, State of Georgia, have invented certain new and useful improvements in Recording-Telephones, of which the following is a specification.

My invention relates to a dictating telephone and more particularly to a device of 10 that character which may be of convenient size and weight for use on an office desk or similar place.

The device is constructed so that it may be used to receive direct dictation for the 15 phonograph, and to receive telephone messages from the ordinary telephone receiver to record the same on a phonograph record.

This application constitutes a modification of my pending application Serial No. 20 876,864.

The objects and novel features of the invention will be apparent from the following description taken in connection with the drawing, in which:

25 Figure 1 is a plan view of a device embodying my invention.

Fig. 2 is a vertical sectional view of the same.

Fig. 2^a is a detail view of a spring.

30 Fig. 3 is a bottom plan view of the device with the base plate removed.

Fig. 4 is a side elevation illustrating a modified form of the invention.

Fig. 5 is a diagrammatic view of the apparatus and the circuits connecting the parts of the mechanism.

Fig. 6 is a vertical-cross sectional view of an improved recorder arranged to fit a standard recorder frame.

40 Fig. 7 is a bottom plan view of the same.

Fig. 8 is a horizontal cross section of the same on the line 8—8 of Fig. 6.

Fig. 9 is a plan view of the counter weight and supporting spring for the recorder frame.

45 Figs. 10 and 11 are perspective views of the improved diaphragms or reeds designed for use on the recorder as shown in Figs. 6 to 8.

50 Referring to Figs. 1 and 2 particularly, the apparatus comprises a stamped sheet metal casing 10 which has an opening 11 in its front side wall and an opening 12 in its top wall. The inside bottom 13 of the casing is held in place by the braces 14 secured to the bottom 13 and front and rear

side walls of the casing. A felt pad 15 covers the outside surface of the bottom wall 13 and is clamped in place at its edges so as to provide a bottom and lateral edges 60 which will not mar the desk.

A telephone transmitter T of the usual or any preferred construction is mounted within the casing 10 and a sound inlet duct 16 is secured to the front face of the casing 65 171 of the transmitter T centrally thereof. The sound inlet duct 16 has a tube 17 connected to its outer end and substantially coaxial with the inlet duct 16. A flexible speaking tube 18 fits into the outer end of 70 the tube 17 which extends in an upward direction through the opening 11 in the front wall of the casing 10. The speaking tube 18 has a flaring mouth piece 19 connected to the outer end thereof, and it is arranged 75 so that it may be bent and will hold any desired adjusted position. The sound inlet 16 has an upwardly extending sound tube or duct 20 connected thereto which extends through the opening 12 in the top of the 80 casing 10 and has a lateral flange 21 which rests on and is secured to the top surface of the casing 10 whereby the transmitter and the parts connected thereto are supported in the casing. The axis of the duct 85 20 is disposed at an angle to the axis of the inlet 16 and tube 17 and consequently the sound waves entering the inlet 16 from the duct 20 will strike the transmitter diaphragm d in a more direct manner than if 90 the duct 20 were mounted at right angles to the tube 17.

At the point where the duct 20 opens into the inlet 16 and on the opposite side of the axis of the duct 20 from the transmitter T 95 is mounted a gate or closure 22. The gate 22 is pivoted at 23 so that it may swing down and prevent communication between the speaking tube 18 and inlet 16 as indicated in dotted lines. The gate 22 is normally in the position shown in Fig. 2 and is held in that position by a rod 24 which has a curved part 25 fitting into a recess 26 in the face of the gate. At its upper end the rod 24 has a button 27 which is engaged on 100 the under side by a flat spring 29, shown in plan in Fig. 2^a. The spring 29 is curved so that it will fit around the outside of the duct 20 and is fastened on the opposite side from the pin 27 by the screw 30. Normally 110 the spring 29 will hold the rod 24 in elevated position and the duct 20 will be closed.

When it is desired to make a phonographic record of a telephone message the receiver R as shown in dotted lines in Fig. 2 is set so that its sound outlet 31 will register with 5 the entrance 32 of the duct 20. The receiver R is supported on a felt ring 33 which is mounted on the flange 21 and held in place by the rim 34 at the edge of, said flange. When the receiver R is set in place it engages 10 the head of the button 27 and depresses the same against the tension of the spring 29 so that the gate 22 will drop into the position shown in dotted lines, opening the duct 20 at the lower end and closing the duct leading 15 from the mouth piece 19.

For dictation purposes the device is set near the edge of the desk and directly in front of the operator with the mouth piece 19 located in the position desired. This allows 20 both hands free to handle the correspondence and gives an unobstructed vision. If preferred the machine may be equipped with a horn similar to the hard rubber horn 38 illustrated in Fig. 4 the outer end of 25 which is flaring and which extends upwardly from the transmitter T.

In Fig. 5 I have shown diagrammatically the circuits which connect the different parts of the mechanism together. The phonograph record medium is indicated diagrammatically at P and is in the form of a cylinder and adapted to be engaged by a stylus 81 carried by a diaphragm 79 which is mounted at its opposite sides in a frame 76. The frame 76 carries an electromagnet consisting of a core 42 and a winding 43. The electromagnet is designed to vibrate the diaphragm 79 and stylus 81, and the winding 43 thereof is connected at one side by the wire 44 to a 30 battery B. The other side of the winding is connected by a wire 45 to the secondary winding 46 of an induction coil I. The other side of the winding is also connected by a wire 47 to a watch case receiver 48. The 35 other terminal on the watch case receiver 48 is connected by a conductor 49 to a condenser 50. The secondary winding 46 and the condenser 50 are connected by the wires 51 and 40 52 respectively to the contact spring 53 of the push button switch 54. It will thus be 45 seen that the secondary winding 46 and the circuit containing the telephone instrument 48 and condenser 50 are in parallel with one another. The transmitter T has one of its 50 terminals connected to an intermediate contact of the battery B by a conductor 55 and its other terminal is connected to the primary winding 56 by a conductor 57. The opposite end of the primary winding 56 of 55 the induction coil is connected to the switch contact spring 58 by a conductor 59.

The two contact springs 60 and 61 are connected by a conductor 62 to the battery B and are forced into contact with the springs 60 65 53 and 58 respectively when the locking push

button 64 is depressed. In order to indicate when the push button 64 is depressed I provide a lamp 65 which is connected by the conductors 66 and 67 to the battery B when the push button is depressed. The push button and lamp are located on the top of the casing 10 as shown in Fig. 1 in a position convenient to the operator. The induction coil I, the condenser 50 and the connection block 68 are all located inside the casing 75 70 where they will be out of the way, the condenser being located directly beneath the lamp 65. As illustrated in Fig. 2 the key extends nearly the entire depth of the case and at its lower end it has two pairs of connecting terminals 641 whereby the proper wires shown in Fig. 5 are connected thereto. The connection block 68 is placed at the extreme bottom of the side wall of the casing 10 and the curvature of the transmitter provides 85 ample room for the same at that part of the casing.

The watch case receiver 48 when not in use is supported in a holder 69 on the outside of the casing 10 and the conductors 47 and 49 90 extend through the hard rubber bushings 70 in the wall of the casing to the connection block 68 which has the terminals 681 thereon for the various circuits.

The watch case receiver 48 is of the standard commercial permanent magnet type but is modified to the extent that the number of turns of fine wire therein has been greatly increased and thereby the instrument becomes more sensitive under utilization in this 100 circuit arrangement than the standard commercial device. The condenser 50 is of small capacity, about one-tenth M. F. capacity and is utilized to choke the receiver circuit and prevents the flow of direct current in that 105 circuit. The highly sensitive watch case receiver is capable of reproducing the vibrations as registered by the receiver R and the volume is not impaired to any great extent. The circuit arrangement permits from 85 to 110 90 per cent. of the voice undulations delivered by the induction coil to be passed to the magnetic recorder.

The dictating telephone is designed to be utilized primarily for correspondence dictation and by the use of the locking key 64 on the casing I overcome any necessity of changes or additions to the commercial phonograph other than that of replacing the regular phonographic recorder with the magnetic recorder.

Referring to Figs. 6 to 11 the improved form of recorder illustrated comprises a substantially cylindrical casing 75 which is threaded at its upper end to receive the screw cap 751 and near its lower end it has a circular projection 752 which provides a shoulder to support the casing in the usual recorder frame of a standard Edison phonograph. The walls of the casing 75 are bored 125 130

to receive bushings 753 which carry the terminal posts 754 by means of which the circuit wires 44 and 45 are connected to the magnet 43 mounted inside the casing.

5 The casing 75 has a downwardly extending portion 755 which has the bifurcated portions 756 at its lower end to receive the arm 761 of a magnet supporting frame 76. The arm 761 is pivoted in the bifurcated 10 parts 756 by means of a pin 762 which passes therethrough. The magnet supporting frame 76 consists of a member of magnetic material bent so as to provide a top portion 763 and two downwardly extending parallel 15 parts 764 and 765. At the lower ends of the parts 764 and 765 are two oppositely outwardly extending arms 766 and 767, extending at right angles to the arms 764 and 765 respectively, the arm 767 being integral with 20 the arm 761 which forms the pivoting support for the magnet carrying frame.

The opposite end of the frame 76 is yieldingly supported by means of a counterweight consisting of a solid block of metal 25 77 which is pivotally supported at the diametrically opposite sides of the casing by the pivot screws 771. A spring plate 772 is fastened to the under side of the counterbalance 77 and has the hook 773 at its outer end 30 to receive a rod 774 which connects the plate 772 to a hook 775 located on the opposite side of the magnet 43 from the pivot 762. In order to adjust the weight 77 I provide a screw 78 which fits a threaded lug 781 on the top 35 side of the weight 77 and which may be set in any adjusted position by a nut 782. It will be obvious that by turning the screw 78 the amount of counterbalancing effect exerted by the weight 77 may be varied and 40 thereby the frame 76 may be lowered or raised at its outer end.

The core 42 of the magnet 43 is secured to the top 763 of the frame 76 by a screw 421 which draws the core into close contact with 45 the frame 76 so that there will be little or no magnetic leakage at the joint. The opposite end of the core 42 extends to a point substantially opposite the center of a diaphragm or reed 79 which consists of a flexible narrow strip of magnetic material which is secured at its opposite ends by the screws 791 and 792 respectively. It will be noticed that the arms 766 and 767 have their bottom faces cut away for part of the length thereof so as 50 to leave prominences 793 and 794 thereon which support the reed or diaphragm 79 a slight distance from the arms leaving the narrow air gaps 795 and 796 between the diaphragm 79 and a portion of the frame. By 55 this arrangement the magnetic flux flowing through the pole pieces 764 and 765 will in part flow across or jump the small air gaps 795 and 796 instead of traveling to the prominences 793 and 794. This arrangement 60 increases the efficiency of the recorder over

that shown in my prior application hereinbefore referred to.

The quantity of the magnetic flux through the magnetic circuit of the electromagnet is normally substantially *nil* and when the 70 electro-magnet is energized an initial quantity of flux will be established in the magnetic circuit.

The construction of the reed of diaphragm used may be either the one shown in Fig. 10 75 or the one shown in Fig. 11, the one shown in Fig. 10 being shown in position. The reed 79 is narrower at the center than at the ends and approximately at its center it has a soft iron disk 80 which is provided 80 with a shoulder 801 which acts as a mounting for the sapphire or stylus 81. The soft iron disk 80 may be secured to the reed or diaphragm 79 by two screws not shown which pass through the circular portion 85 of the reed at the center or the center portion of the reed may be provided with integral upturned clips 802 which engage opposite sides of the disk 80 and hold it in position. In order to dampen the vibrations and prevent cuttings and other foreign substances from getting between the end of the core 42 and the diaphragm 79 I employ a felt washer 82 which surrounds the end of the core and fits between the magnet 95 and diaphragm.

I find that for some purposes a reed constructed of the same width from end to end is preferable. This form is shown in Fig. 11 and approximately at its center is mounted a square soft iron disk 80' which is held in place by clips 802' and on its under side has a shoulder for supporting the sapphire in the same way as that shown in Fig. 6. In this form a felt washer is also employed and 100 surrounds the lower end of the magnet core. 105

The soft iron sapphire mounting is beneficial because it loads the center or approximate center of the reed and eliminates the metallic sound. The amplitude of the reed 110 is also increased and I am enabled to use a reed of larger gage mild steel than in the device described in my former application referred to above.

By loading the center of the reed, a hammer effect is obtained which is desirable in this apparatus. Primarily however the arrangement affords greater mass for the magnetic flux in proximity to the core of the magnet and being of greater diameter than the core of the magnet eliminates oversaturation of the reed or dissipation of magnetic flux at the point opposite the core of the magnet.

While I have shown and described the device in detail I do not wish to be limited to the exact construction set forth as various modifications may be made therein without departing from the spirit of the invention.

Having thus described my invention, what 125 130

I claim and desire to secure by Letters Patent is:

1. In an apparatus of the class described, the combination of a phonographic record medium, a diaphragm, a stylus carried by the diaphragm and an electromagnet in which the quantity of magnetic flux is normally substantially *nil* associated with said diaphragm and stylus, said magnet comprising a soft iron core and a single winding, a transmitter, direct current supply means, and means for closing circuits through said transmitter and through said electromagnet so that direct current may flow through both the transmitter and electromagnet and thereby establish an initial quantity of magnetic flux in said electromagnet. 10
2. In an apparatus of the class described, the combination of a phonographic record medium, a diaphragm, a stylus carried by the diaphragm, an electromagnet for vibrating said diaphragm and stylus, a transmitter, an induction coil having one winding connected to said transmitter and the other winding connected to said electromagnet, direct current supply means, and means for closing the circuits through said transmitter, induction coil and electromagnet so 20 that direct current may flow through the transmitter, windings of the induction coil, and electromagnet. 30
3. In an apparatus of the class described, the combination of a phonographic record medium, a diaphragm, a stylus carried by the diaphragm, an electromagnet in which the quantity of magnetic flux is normally substantially *nil* and associated with said diaphragm and stylus, a transmitter, an induction coil having one winding connected to said transmitter and the other winding connected to said electromagnet, direct current supply means, and a switch device having contacts connected to the windings of 35 the induction coil and to the direct current supply means and adapted to close the circuits through said transmitter, induction coil, and electromagnet and thereby establish an initial quantity of magnetic flux in 40 said induction coil and electromagnet. 45
4. In an apparatus of the class described, the combination of a phonographic record medium, a diaphragm, a stylus carried by the diaphragm, an electromagnet for vibrating said diaphragm and stylus, a telephone transmitter, a battery, an induction coil having its primary winding connected to the telephone transmitter and having its secondary winding connected to the electromagnet, and a push button switch device having separate contacts connected to the primary and secondary windings of the induction coil and to the battery and adapted to connect said battery with said windings 55 so that direct current from said battery may 60
- flow through said windings and through the transmitter and electromagnet. 65
5. In an apparatus of the class described, the combination of a phonographic record medium, a diaphragm, a stylus carried by the diaphragm, an electromagnet for vibrating said diaphragm and stylus, a telephone transmitter, an induction coil having a primary winding connected to the telephone transmitter and a secondary winding 70 connected to the electromagnet, a battery connected to said transmitter and to said electromagnet, a telephone instrument and a condenser connected in parallel circuit with the secondary winding of said coil, and means for connecting the windings of the induction coil and the circuit including said telephone instrument and condenser to said battery so that current may flow 75 through said transmitter and electromagnet. 80
6. In an apparatus of the class described, the combination of a phonographic record medium, a diaphragm, a stylus carried by the diaphragm, an electromagnet for vibrating said diaphragm and stylus, a telephone transmitter, an induction coil having a primary winding connected to the telephone transmitter and a secondary winding 90 connected to the electromagnet, a battery connected to said transmitter and to said electromagnet, a telephone instrument and a condenser connected in parallel circuit with the secondary winding of said induction coil, a push button circuit closer having contacts connected to the primary and secondary windings of said induction coil, to the circuit including said condenser and telephone instrument, and to said battery and adapted to close the circuits through said transmitter and through said electromagnet 95 100 so that current may flow through the transmitter and electromagnet, and a lamp adapted to indicate when said push button is in closed position. 105
7. In an apparatus of the class described, the combination of a casing, a telephone transmitter inside the casing, said transmitter having a sound inlet, and a sound duct connected at one end to the sound inlet of said transmitter and extending outside 110 of the casing and upwardly therefrom. 115
8. In an apparatus of the class described, the combination of a casing having an opening in its top wall and an opening in a side wall thereof, a telephone transmitter in the casing and having a sound inlet, and sound ducts leading from the openings in said casing to the sound inlet of the transmitter. 120 125
9. In an apparatus of the class described, the combination of a telephone transmitter having a sound inlet, a sound duct connected with said sound inlet and having a part coaxial with said sound inlet of the transmitter, and a second sound duct opening into 130

- the first mentioned sound duct and having its axis inclined to the axis of said first mentioned sound duct whereby sound waves entering from said second sound duct into the 5 first mentioned sound duct will strike the wall of the first mentioned sound duct at an inclination so as to be deflected into the inlet in said transmitter.
10. In an apparatus of the class described, 10 the combination of a casing having an opening in the top and in one side thereof, a telephone transmitter in said casing having a sound inlet, a flexible speaking tube having one end extending through the opening in 15 the side wall of the casing and connected with the sound inlet of said transmitter, a sound duct leading through said opening in the top of the casing to the inlet of said transmitter, a condenser, an induction coil, 20 and terminal posts located inside said casing and connected to said transmitter, a push button switch mounted on the casing and a signal lamp mounted on the casing.
11. In an apparatus of the class described, 25 the combination of a casing having an opening in its top wall and an opening in one of its side walls, a telephone transmitter inside said casing having a sound inlet, a duct leading through the side opening in said casing 30 and connected to said sound inlet and a second duct leading through the top opening in the casing to the sound inlet of said transmitter, said second duct having a lateral flange which is secured to said casing.
- 35 12. In an apparatus of the class described, the combination of a casing having an opening in its top wall and an opening in one of its side walls, a telephone transmitter inside said casing having a sound inlet, a duct leading 40 through said opening in said casing and connected to said sound inlet, a second duct leading to the sound inlet of said transmitter and having a lateral flange secured to the top of said casing, and means for supporting a
- telephone receiver so that its sound outlet 45 will register with the entrance of said second duct, for the purpose set forth.
13. In an apparatus of the class described, the combination of a telephone transmitter having a centrally arranged sound inlet, a 50 sound duct connected to said inlet and having a part coaxial therewith, a second sound duct leading to said sound inlet of the transmitter and having its axis inclined to the axis of said sound inlet, and a gate pivoted 55 so as to prevent the transmission of sound waves from either one of said ducts to said inlet, said gate being pivoted on the opposite side of the axis of said second duct from said transmitter whereby sound waves entering 60 at an inclination to the axis of said sound inlet in the transmitter will be deflected into the latter.
14. In an apparatus of the class described, the combination of a casing having openings 65 in its walls, a telephone transmitter in the casing having a sound inlet, sound ducts leading through said openings in the walls of the casing to the sound inlet of said transmitter, and a support for a telephone 70 instrument on the outside of said casing.
15. In an apparatus of the class described, in combination, a phonographic record medium, a diaphragm, a stylus carried by the diaphragm, an electro-magnet in which the 75 quantity of magnetic flux is normally substantially *nil* associated with said diaphragm, a transmitter, a circuit including said magnet, a circuit including said transmitter, a source of direct current for said 80 circuits, and means whereby changes in the circuit containing the transmitter cause changes in the circuit having the magnet.

In testimony whereof I affix my signature.
JOHN F. MALTHANER.

Witness:
W. E. SIMPSON.
